Elmer F. Oettinger, Buffalo, N. Y.

Application May 12, 1950, Serial No. 9,909

Term of patent 3½ years

(Cl. D55—1)

To all whom it may concern:

Be it known that I, Elmer F. Oettinger, a citizen of the United States, residing at Buffalo, in the county of Erie and State of New York, have invented a new, original, and ornamental Design for a Combination Bun and Roll Slicer, of which the following is a specification, reference being had to the accompanying drawing, forming a part thereof.

Figure 1 is a front elevation of the combination bun and roll slicer embodying my new design. Figure 2 is a right end view thereof. Figure 3 is a left end view of the same. Figure 4 is a top plan view thereof. Figure 5 is a rear view thereof.

I claim:

The ornamental design for a combination bun and roll slicer substantially as shown.

ELMER F. OETTINGER.
